UNITED STATES PATENT OFFICE.

FRANK A. McGUIRE, OF IOLA, KANSAS.

WICK-HOLDER.

1,299,977.

Specification of Letters Patent.

Patented Apr. 8, 1919.

Application filed December 14, 1918. Serial No. 266,785.

To all whom it may concern:

Be it known that I, FRANK A. McGUIRE, a citizen of the United States, and a resident of Iola, in the county of Allen and State of Kansas, have invented certain new and useful Improvements in Wick-Holders, of which the following is a specification.

My invention is an improvement in wick holders, especially designed for use with 10 sanctuary lamps to support the wick in the lamp in such manner that it may be easily removed without the necessity for touching the same with the hands, and without the necessity for touching the oil, and wherein 15 the remnants of burnt wick may be expelled by the insertion of the new, and wherein the wick will be firmly held, but in a yielding manner, to provide for use of different sized wicks.

20 In the drawings:

Figure 1 is a perspective view of the improved holder, showing the insertion of a new wick;

Fig. 2 is a sectional view of the lamp, with 25 the wick and holder in place;

Fig. 3 is a section through the wick bearing;

Fig. 4 is a similar view through a modified construction;

30 Fig. 5 is a partial perspective view of the holder, showing the means for adjusting the length of the holder.

In the present embodiment of the invention the holder is extensible and contractible, 35 consisting of sections 1 and 2, the said sections being of strip formation as shown.

The strip 2 has a species of socket at its upper end formed by lateral enlargements, which are bent over to form guide flanges 3, 40 and the adjacent end of the section 1 moves in these guide flanges. The section 1 has a species of hook or clasp 4 at its top, which will engage over the frame of the vessel 5, to support the holder in proper position in 45 the vessel, and at the hook or clasp the section has a fingerpiece 6 in the form of a ring, which may be grasped by the fingers, as shown in Fig. 1, to remove the holder from the vessel.

50 The lower end of the section 2 is curved laterally at approximately a right angle to the body of the section, as indicated at 7, and this lateral portion 7 carries a socket 8 for receiving the wick 9. Referring to Fig. 55 3, it will be noted that the socket is of larger diameter than the wick, so that the wick

moves loosely in the socket, and yielding mechanism is provided for engaging the wick to hold it firmly in place, to permit the wick to be moved longitudinally of the 60 socket.

The holding means shown in Fig. 3 is in the form of a ring 10 which is inserted in the lower end of the socket and has spring 65 tongues 11 which engage the wick. The ring 10 is held in place by a radial lug 12 which is bent around the end of the portion 7 of the strip, as clearly shown in Fig. 3.

In Fig. 4 the socket 13, which corresponds to the socket 8 of Fig. 3, receives the wick 14, 70 and the wick is held in place by a spring tongue 15. This tongue is secured to the end of the portion 7^a corresponding to the portion 7 of Fig. 1 by means of a lug 15 which is bent around and over the end of 75 the portion 7^a. In either case the wick may be moved freely upward through the socket to bring the blaze at the proper point with respect to the vessel.

In inserting a new wick, it is inserted from 80 below, as shown in Fig. 1, being passed upwardly through the socket, and the end of the entering wick will displace the unburnt remnant of the old wick. Thus the unburnt remnant may be dislodged and the new wick 85 inserted without the necessity of touching the holder, except at the finger piece 6. Also the holder may be removed, together with the wick, from the vessel without necessitating touching the oil.

90 A limited amount of adjustment is permitted between the sections to correspond with vessels of different depth, and it will be evident, referring to Figs. 3 and 4, that wicks of different sizes may be used and will 95 still be held by the socket. In practice, a heavy wick is used in cold weather, while one of smaller size is used in warm weather.

It will be understood that bushings may be used in the socket to firmly engage the 100 wicks to hold them from movement, that is, from accidental displacement. Thus for thin wicks thick bushings would be used, while for thick wicks thin bushings would suffice.

I claim:

1. A wick holder of the character specified 110 consisting of a strip bent at its upper end to form a hook for engaging over the edge of a vessel and having a finger piece at the hook, and bent at its lower end to lie at approximately a right angle to the body of the strip, said last named end carrying a socket

- through which the wick may be passed, the socket having yielding means for engaging the wick to hold the same, said strip consisting of sections slidably connected.
5. 2. A wick holder of the character specified consisting of a strip bent at its upper end to form a hook for engaging over the edge of a vessel and having a finger piece at the hook, and bent at its lower end to lie at approximately a right angle to the body of the strip, said last named end carrying a socket through which the wick may be passed, the socket having yielding means for engaging the wick to hold the same.
10. 3. A wick holder of the character specified consisting of a strip bent at its upper

end to form a hook for engaging over the edge of a vessel and having a finger piece at the hook, the other end of the strip carrying a socket through which the wick may be 20 passed, and yielding means in the socket for engaging the wick.

4. A wick holder for the purpose specified comprising a strip having at one end means for engaging the edge of a vessel and having 25 at the other end a socket through which the wick may be passed, said socket having yielding means for engaging the wick.

FRANK A. McGUIRE.
